UNITED STATES PATENT OFFICE.

GILBERT M. SCHERER, OF NEW YORK, N. Y.

PHONOGRAPH.

1,331,788.

Specification of Letters Patent. Patented Feb. 24, 1920.

Application filed December 28, 1917. Serial No. 209,248.

To all whom it may concern:

Be it known that I, GILBERT M. SCHERER, a citizen of the United States, residing at New York, borough of Manhattan, in the 5 county and State of New York, have invented certain new and useful Improvements in Phonographs, of which the following is a full, clear, and exact description.

The invention, which constitutes the subject matter of this application, relates, in its broader aspect to several features of novelty, one of which comprises mechanism for raising and lowering a phonograph record of the disk type from the rotating disk or table 10 upon which the record is mounted. This mechanism enables the record to be raised for the purpose of removal and also facilitates the replacement or the placing of another record thereon. Other features of this 15 invention reside in the simplicity and construction of the mechanism and will appear from the detailed description below, taken in connection with the accompanying drawings, in which

20 Figure 1 is a front view, partly in section, illustrating one application of my invention.

25 Fig. 2 is a side view of the mechanism employed in raising a record from and lowering the same upon the disk.

30 Fig. 3 is a top plan view of the mechanism illustrated in Fig. 2 with the reciprocating support of Fig. 4 omitted therefrom.

35 Fig. 4 is a plan view of the member for holding the record in elevated position.

40 Referring to the drawings in detail, the reference numeral 10 indicates the upper portion of an ordinary phonograph cabinet of conventional construction, in connection with which there is provided the usual rotating disk 11 carried by the actuating shaft 12. The features I have just described are all old and well-known and I make no claim broadly thereto, except as they constitute a part of the combination which I shall now 45 proceed to describe.

45 Mounted upon the rotating disk 11 is a fabric 13, provided at its center with a circular opening 14 adapted to receive the member 15 of the disk raising mechanism.

50 There is a part 16 below the face of the rotating disk 11, which corresponds to the part 15. These parts 15 and 16 are illustrated as being made of solid disks; but it will be understood that this is merely the 55 preferred form and that they may be skeletonized and changed in other manner with-

out departing from my invention. Connecting the two members 15 and 16 are a plurality of posts 17, preferably three in number which reciprocate in a corresponding 60 number of perforations 18 in the rotating disk 11.

It will of course be understood that the reciprocation of the members 15, 16 serves to raise the record disk from and lower the 65 same upon the rotating disk 11. In Fig. 1 the record disk is in position to be lowered upon the disk 11 or to be removed from the member 15.

In conjunction with the elevating mechanism just described I employ means for actuating same so as to raise the record from the rotating disk 11 and lower same thereon. This mechanism I will now proceed to describe.

Upon the upper surface of the cabinet 10, I provide a securing member 19, to which is pivotally connected a double armed lever 20, the outer ends of which are provided with anti-friction members 21, which bear 70 against the lower side of the member 16. To the plate 19 is also pivoted an operating lever 22, one end of which is provided with a handle 23 and the other end of which is pivotally connected through slot 23^a to 75 the arm 24, which is provided with a slot 25 to receive the pivot 26. The inner end of the arm 24 is provided with a cam face 27. The double armed lever 20 is provided with a lateral stud or projection 28 and engages the cam face 27 of the lever 24. The purpose of the slots 23^a and 25 in conjunction with the pivots 24 and 26 is to enable the lever 24 to reciprocate back and forth in substantially the same lineal path. 80

85 The operation of the above described mechanism is as follows: The operator takes hold of the handle 23, and moves the lever 22 toward the indication "Lower". This withdraws the cam face 27 from under the lateral projection 28 and enables the double 90 armed lever 20 and the supporting mechanism 15-16 to move downwardly. This lowers the record upon the disk 11. A movement of the lever 22 in the opposite 95 direction, that is to say, toward the indication "Raise", will elevate the record from the rotating disk 11, as will be understood.

What I claim is:

1. In a sound reproducing machine, a rotatable record support, in combination with means adapted to elevate a record from said 100

support to facilitate its removal comprising a member carried by and movable axially with respect to said record support, in combination with means for effecting said axial 5 movement of said member.

2. In a sound reproducing machine, a rotatable record support, in combination with means to elevate a record from said support to facilitate the removal of said record, comprising an elevating means carried by said support, and means for raising and lowering 10 said elevating means.

3. In a sound reproducing machine, in combination, a rotatable record support, 15 means axially movable with respect to said support for facilitating removal of a record from said support when the latter has been stopped in any position, and means for effecting movement of said first-named 20 means.

4. In a sound reproducing machine, in combination, a rotatable record support, means movable to a position above said support to disengage a record therefrom re- 25

gardless of the position of said support and 25 means for moving said first-mentioned means to its operative position.

5. In a sound reproducing machine, in combination, a stationary support, a record support rotatably mounted with respect 30 thereto, means carried by said record support for moving a record with respect thereto and means mounted on said stationary support for actuating said first-mentioned means. 35

6. In a sound reproducing machine, in combination, a rotatable record support, means for causing a relative movement between said support and a record to facilitate removal of the latter, said means and 40 support being mounted for relative axial movement when said support is in any position with respect to its axis of rotation, and means for effecting a relative movement of said support and first-mentioned means. 45

In testimony whereof I hereunto affix my signature.

GILBERT M. SCHERER
